CLAIM

The ornamental design for an optic fitting set, as shown and described.

DESCRIPTION

FIG. 1 is an exploded perspective view of an optic fitting set, according to a first embodiment;

FIG. 2 is an assembled perspective view of the optic fitting set of FIG. 1;

FIG. 3 is a perspective view of a receiving element for the optic fitting set of FIG. 1;

FIG. 4 is a top view of the receiving element of the optic fitting set of FIG. 3;

FIG. 5 is a forward side elevational view of the receiving element of the optic fitting set of FIG. 3;

FIG. 6 is a rear side elevational view of the receiving element of the optic fitting set of FIG. 3;

FIG. 7 is a bottom view of the receiving element of the optic fitting set of FIG. 3;

FIG. 8 is a top view of an insertion member of the optic fitting set of FIG. 1;

FIG. 9 is a bottom view of the insertion member of the optic fitting set of FIG. 8;

FIG. 10 is a forward side elevational view of the optic fitting set of FIG. 8;

FIG. 11 is a rear side elevational view of the optic fitting set of FIG. 8;

FIG. 12 is an exploded perspective view of an optic fitting set, according to a second embodiment;

FIG. 13 is an assembled perspective view of the optic fitting set of FIG. 12;

FIG. 14 is a perspective view of a receiving element for the optic fitting set of FIG. 12;

FIG. 15 is a top view of the receiving element of the optic fitting set of FIG. 14;

FIG. 16 is a forward side elevational view of the receiving element of the optic fitting set of FIG. 14;

FIG. 17 is a rear side elevational view of the receiving element of the optic fitting set of FIG. 14;

FIG. 18 is a bottom view of the receiving element of the optic fitting set of FIG. 14;

(Continued)

FIG. 19 is a top view of an insertion member of the optic fitting set of FIG. 12;
 FIG. 20 is a bottom view of the insertion member of the optic fitting set of FIG. 19;
 FIG. 21 is a forward side elevational view of the optic fitting set of FIG. 19;
 FIG. 22 is a rear side elevational view of the optic fitting set of FIG. 19;
 FIG. 23 is an exploded perspective view of an optic fitting set, according to a third embodiment;
 FIG. 24 is an assembled perspective view of the optic fitting set of FIG. 23;
 FIG. 25 is a perspective view of a receiving element for the optic fitting set of FIG. 23;
 FIG. 26 is a top view of the receiving element of the optic fitting set of FIG. 25;
 FIG. 27 is a forward side elevational view of the receiving element of the optic fitting set of FIG. 25;
 FIG. 28 is a rear side elevational view of the receiving element of the optic fitting set of FIG. 25;
 FIG. 29 is a bottom view of the receiving element of the optic fitting set of FIG. 25;
 FIG. 30 is a top view of an insertion member of the optic fitting set of FIG. 23;
 FIG. 31 is a bottom view of the insertion member of the optic fitting set of FIG. 30;
 FIG. 32 is a forward side elevational view of the optic fitting set of FIG. 30; and,
 FIG. 33 is a rear side elevational view of the optic fitting set of FIG. 30.
 Any broken lines illustrate portions of the optic fitting set that form no part of the claimed design.
